UNITED STATES PATENT OFFICE.

ELIHU THOMSON, OF SWAMPSCOTT, MASSACHUSETTS, ASSIGNOR TO GENERAL ELECTRIC COMPANY, A CORPORATION OF NEW YORK.

MEANS FOR PREVENTING CORONA LOSS.

1,157,344.

Specification of Letters Patent.

Patented Oct. 19, 1915.

Application filed December 28, 1912. Serial No. 739,006.

To all whom it may concern:

Be it known that I, ELIHU THOMSON, a citizen of the United States, residing at Swampscott, in the county of Essex, State of Massachusetts, have invented certain new and useful Improvements in Means for Preventing Corona Loss, of which the following is a specification.

My invention relates to electric conductors, and more particularly to conductors which are to be subjected to potentials so high that if the conductors are the solid wires generally used corona will appear upon them. If the voltage between the two wires of a transmission line, for example, is gradually increased, it ultimately reaches a point where corona is produced because the air surrounding the wires breaks down. As the voltage gradually increases, the zone of broken down air surrounding each wire spreads farther and farther from the wire, thereby enlarging the luminous zone of corona until these zones have spread to such an extent that they merge into each other, whereupon a conducting path between the wires is established and the line may be short-circuited. This phenomenon may also be considered with reference to the electrostatic field which surrounds two conductors carrying current. Each conductor is surrounded by a magnetic field which may be represented by lines of force forming circles around each conductor, while at the same time the voltage between the wires produces a condition of electrostatic stress which may be represented by lines of electrostatic force issuing from the conductor perpendicular to the surface of the wire and intersecting the circles which represent the lines of magnetic force around the conductor. The density of the lines of electrostatic force will be proportional to the voltage per centimeter length of the electrostatic circuit, and, if the number of lines of electrostatic force per inch in air rises beyond a certain critical value, the air breaks down.

For any given size of wire and distance apart of wires, there is a certain critical voltage at which the critical density of the electrostatic lines of force or the critical voltage gradient is reached, whereupon the air breaks down and luminosity begins. This is the critical voltage at which corona appears. At higher voltages the corona extends to

greater distances from the conductor and a 55 greater volume of air becomes luminous. Up to the critical voltage there is practically no loss from corona, but beyond the critical voltage the corona losses increase very rapidly. A simple method of determining 60 the critical voltage or the voltage where the corona formation begins is to raise the voltage between the wires gradually and in darkness until the luminosity begins. It is found that the point between where the wire 65 is dark and where it is luminescent can be measured within the fraction of one per cent.

At high voltages a small current is sufficient to convey a large amount of energy and 70 therefore at high voltages a small conductor is ordinarily large enough to carry as much energy as is usually transmitted over a conductor. As the critical voltage of a small wire is lower than that of a large wire, the 75 corona losses will be prohibitive on high voltage conductors, such as the wires of a transmission line, unless the conductors are much larger than is necessary to make them 80 strong enough to resist mechanical strains or to have sufficient current carrying capacity.

The object of my invention is to provide a conductor containing only the minimum amount of metal necessary to carry the current and with a greater virtual diameter 85 than actual diameter. To such a conductor much higher potentials can be applied without causing the appearance of corona than can be applied to conductors of the type heretofore used, and therefore the commercial use of potentials much higher than those 90 heretofore commonly used commercially becomes feasible.

My invention will best be understood in connection with the accompanying drawing 95 which merely for purposes of illustration shows one of the forms which at the present time I consider to be the best embodiment of the principle of my invention and in which is shown one form of a conductor constructed 100 in accordance with my invention.

In the particular embodiment of my invention shown in the drawing, a conducting element or wire 1 of the proper size to convey the current with proper economy is 105 covered with a conducting sheath 2, which enlarges the virtual diameter of the wire to such an extent that a voltage much above

the critical voltage of the bare wire 1 can be applied to the conductor without causing the production of corona. I prefer to make the conducting sheath 2 of some very light material, such as cotton fiber filled with a little graphite 3 or other suitable conducting material, and then smoothed on the outside by drawing through dies or any other suitable way, after which it may be 5 slightly impregnated with some compound to preserve it from the weather. Any suitable fibrous material may be used instead of the cotton fiber and may be coated with any suitable conducting material, such, for example, as linseed oil, in which fine graphite, lampblack or charcoal has been mixed to form a conductive body. Since the material of the conducting sheath 2 has only to convey at high voltage a very small current 10 from the wire to the outside of the sheath and back again during the alternations in current on the conducting element 1, the sheath need be of only sufficient conductivity to conduct without appreciable resistance losses the exceedingly small amount of current which passes from the wire 1 to charge the external surface of the conducting sheath 2. The whole covering or conductive sheath of the wire is in effect made 15 up of innumerable radial paths connected in parallel and of a length from the surface of the wire 1 to the outside of the sheath or coating 2. Since all of these paths are in parallel the resistance to radial current flow is very slight and at the high voltages for which the conductor is adapted a sufficient amount of current will flow without appreciable resistance loss to virtually 20 enlarge the diameter of the wire 1 to such an extent that corona does not appear at voltages above the critical voltage of the wire 1 without the sheath. The resistance losses due to radial current flow are practically nothing. The losses which would be 25 caused if the conducting coating 2 were absent and corona were permitted to form around the conducting element 1 are avoided.

My invention may be carried out in many 30 other forms than that shown and described and I, therefore, do not desire to limit myself to the precise arrangement herein set

forth, but intend to cover all modifications within the scope of the appended claims.

What I claim as new and desire to secure 55 by Letters Patent of the United States, is:—

1. A high potential conductor comprising a conducting core, and a non-metallic sheath having sufficient radial conductivity to transmit without resistance loss sufficient 60 current to charge the external surface of said sheath to the potential of said core.

2. A high potential conductor comprising a metal core and a non-metallic sheath having radial conductors distributed through it 65 and in contact with said core to provide a radial conducting path of great total cross-section and extending from said core to the surface of said sheath and having a total cross-section sufficient to eliminate resist- 70 ance losses in radial flow of current.

3. A high potential conductor comprising a conducting element and a sheath having sufficient conducting particles distributed through the body thereof along said conducting element to permit current to flow 75 from said conducting element to the surface of said sheath with no appreciable resistance loss.

4. A high potential conductor comprising 80 a conducting element and a fibrous sheath for said element having conductive particles so distributed through the body thereof that radial conducting paths in parallel are formed of such aggregate cross-section that 85 current may flow radially through said sheath with substantially no resistance losses.

5. In a high potential conductor for transmission lines, the combination with a conducting element, of a fibrous covering for 90 said element having a smooth outer surface and conducting material uniformly distributed through said covering to form radial conducting paths in parallel and enable current to flow radially through said covering 95 with slight loss at the normal operating voltage of the transmission line.

In witness whereof, I have hereunto set my hand this 24th day of December, 1912. 100
ELIHU THOMSON.
